UNITED STATES PATENT OFFICE.

JOSEPH LANG, OF MANNHEIM, GERMANY.

IRON STAIRCASE WITH FLAGSTONE STAIRS.

1,073,250.

Specification of Letters Patent. Patented Sept. 16, 1913.

Application filed May 17, 1913. Serial No. 768,375.

To all whom it may concern:

Be it known that I, JOSEPH LANG, a subject of the German Emperor, residing at 15 Werftstrasse, Mannheim, Germany, have 5 invented a certain new and useful Iron Staircase with Flagstone Stairs, of which the following is a specification.

The object of the invention is a fireproof, cut, housed or bracketed stair-case for residential and business houses in which the two strings are constructed of iron, and the treads, sometimes also the risers, of flag stones. In the known stair-cases of this kind there are fixed to the strings or their 10 brackets angle irons and the flag stones are fixed to these by means of screws. According to this present invention, however, the transverse rails which connect together the two strings serve at the same time for fixing the covering without the assistance of screws or rivets. These rails are provided 15 as gutters and before the flag stones are placed in position are filled with cement, gypsum, or a similar material which when hardening firmly clings to the flags. The 20 advantage of this construction, in comparison with known constructions, consists in that the covering is strengthened by the transverse rails. While building wooden 25 boards can be placed on the transverse rails instead of the flag stones so that the staircase can be used during the building operations, at the same time saving the flag stones. The treads are advantageously supported 30 by two transverse rails, one at the front and one at the rear end, and the front transverse rail of one tread and the rear transverse rail of the next lower rail are formed in one piece with the riser disposed 35 between them. In this manner special 40 risers are not required.

The object of the invention is illustrated in the accompanying drawings.

Figure 1 shows a bracketed stair-case 45 partly in side elevation and partly in longitudinal section. Fig. 2 is a section on the line A A of Fig. 1. Fig. 3 is a cross section of the line B B. Fig. 4 is a cross section corresponding to Fig. 2 of a modification. 50 Fig. 5 shows a string and a transverse rail connected thereto in plan. Fig. 6 is the front string of a housed stair-case in cross section and Fig. 7 is a stair of a further modification in longitudinal section. 55 The two iron strings *a* are connected together by iron transverse rails *b*, in Fig. 1

three and in Fig. 7 two such rails are provided for each stair tread. These rails are at both ends riveted to cheeks *c* which are stamped from the brackets *d* of the strings *a* and bent inward. To the rails *b* are fixed the treads *e* consisting of flag stones and in Fig. 1 also the risers *f*. The rails *b* formed as gutters are filled with cement, gypsum, or a similar material which when 60 hardening clings to the flags *e* or *f* which have been placed in position. In order that the filling may be retained in the rails the latter can be of swallow tail cross section (Fig. 1) or when of semi-circular cross section provided with an inwardly turned edge *b*¹ (Fig. 7).

According to the constructional form shown in Fig. 7 the front supporting rail *b* of one tread *e* and the rear supporting rail *b* of the next lower tread, with the intermediate riser *f*, are constructed in one part, therefore combined to form a single rail.

The front string *a* and its brackets *d* are covered as shown in Figs. 1 and 2 with flag stones *g* and in Fig. 4 with sheets of metal *g*¹ which are held in position by decorative laths *h*. In Fig. 4 the lower decorative lath simultaneously serves for holding the lower covering *i* of the stair-case in position. 80 The upper decorative lath *h* of the brackets *d* as shown in Figs. 2 and 4 can also be provided with a gutter which is filled with cement or the like in order to afford a further hold to the tread *e*. 90

What I claim as my invention and desire to secure by Letters Patent is:—

1. In an iron stair-case the combination of two iron strings, a number of iron transverse rails connecting together said strings, 95 a number of treads consisting of flag stones and placed upon said rails, the latter being formed as gutters and filled with an artificial stone mass which when hardening clings to said treads.

2. In an iron stair-case the combination of two iron strings provided with a number of brackets, cheeks stamped from said brackets, a number of iron transverse rails fixed at both ends to said cheeks and thus 105 connecting together said strings, a number of treads consisting of flag stones and placed upon said rails, the latter being formed as gutters and filled with an artificial stone mass which when hardening clings to said 110 treads.

3. In an iron stair-case the combination

of two iron strings, a number of iron transverse rails connecting together said strings, a number of treads consisting of flag stones and placed upon said rails, two rails being provided for each of said treads, a number of iron risers, the front supporting rail of one tread and the rear supporting rail of the next lower tread being constructed in one part with the intermediate riser, and said rails being formed as gutters and filled

with an artificial stone mass which when hardening clings to said treads.

In testimony whereof I have hereunto signed my name to this specification in the presence of two subscribing witnesses.

JOSEPH LANG.
